UNITED STATES PATENT OFFICE.

JOSEPH DAVIDSON, OF ROCKAWAY BEACH, NEW YORK, ASSIGNOR TO FANNY DAVIDSON, OF ROCKAWAY BEACH, LONG ISLAND, NEW YORK.

DESIGN FOR A DIAMOND-SETTING.

58,307.

Specification for Design.

Patented July 12, 1921.

Application filed November 20, 1920. Serial No. 425,576. Term of patent 7 years.

To all whom it may concern:

Be it known that I, JOSEPH DAVIDSON, a citizen of the Kingdom of Roumania, residing at Rockaway Beach, Long Island, New York, have invented a new, original, and ornamental Design for a Diamond-Setting, of which the following is a specification, reference being had to the accompanying drawing, forming part thereof.

The figure is a top plan view of the diamond setting showing my new design.

I claim:

The ornamental design for a diamond setting as shown.

In testimony whereof I have affixed my signature in presence of two witnesses.

JOSEPH DAVIDSON.

Witnesses:

MAX D. ORDMAN,
JOSEPH T. McMAHON.
